RACK

Joyce C. Hall, Kansas City, Mo.

Application January 30, 1935, Serial No. 4,007

3 Claims. (Cl. 211—55)

My invention relates to counter or floor racks for displaying cards or other flat articles, and has for its principal object to provide a device of that character whereby cards or the like arranged in vertical rows in the rack may be similarly viewed from the same elevation regardless of vertical position of the cards in the rack.

For accomplishing this object I provide a rack including means for supporting the articles to be displayed in vertical rows with their front faces in progressively variable inclined planes, all substantially perpendicular to lines of vision, having a common focal point at a distance from and elevation relative to the rack corresponding to the eye of an observer of average height.

In the accompanying drawing, illustrating a preferred form of my invention:

Fig. 1 is a perspective view of a rack embodying my improvements, showing the different inclinations at which cards are supported in the several vertical rows.

Fig. 2 is an enlarged vertical section of the rack, particularly illustrating the progressive inclination of the several card holders and the means for effecting such inclination.

Fig. 3 is an enlarged perspective view of a portion of the rack, particularly illustrating assembly of the card holders in the rack.

Referring more in detail to the drawing:

1 designates an assembled rack including end members 2 having bottom edges 4 adapted for supporting the rack upon a counter or floor 5.

The end members 2 are high at the back and low at the front and have upper edges curved inwardly and downwardly on an arc of gradually diminishing radius for a purpose presently disclosed.

Extending between and secured to the end members 2 are downwardly and forwardly stepped bars 6, each having parallel upper and lower faces 7—8, a rear face 9 perpendicular to the top and bottom faces, and an upwardly and rearwardly inclined front face 10, all of the bars being similarly dimensioned but arranged at progressively downward and rearward inclinations; the top bar 6—A being substantially horizontal and the bottom bar 6—X having marked angularity as particularly disclosed in Fig. 2.

The front faces of all the bars having the same angularity to their parallel top and bottom faces extend at progressively downward and forward inclinations relative to each other.

The bar 11 of the bottom holder has a rectangular base 12 extended to form a triangular head 13, one face of which seats on the counter

5 and the other of which extends perpendicular-
ly to the floor, the contour of the edges of the
lower portions of the ends 2 conforming to the
outer faces of the bar 11 to provide symmetrical
appearance as well as support for the rack 5
members.

Attached at their upper edges to the inclined
forward edge of each of the bars 6 and at their
lower edges to the rear edge of the next lower
bar 6 are back members 14, progressive inclina- 10
tion of the front faces of the bars thus insuring
projection of the back members in likewise pro-
gressively inclined planes.

In assembling the holders, if the rack is to be
supported on a counter or at like elevation, the 15
bottom member of the upper holder is arranged
substantially horizontally to support cards or
other flat articles substantially perpendicular
to a line of vision substantially horizontal for a
person of average height. The inclination of 20
the lower holders progresses successively so that
the back and bottom bars of the lowermost
holder extend in planes approximately 45° to
the horizontal but at right angles to each other,
thus adapting it for retaining the cards or other 25
flat articles always in a plane approximately per-
pendicular to the line of vision of an observer of
average height viewing the cards in the lower
holder from the same position at which he views
the cards in the upper holder; the angularity of 30
the intermediate holders likewise insuring sup-
port of the cards or other flat articles therein
also at right angles to such line of vision from
such viewpoint so that the observer and possible
purchaser is afforded a clear and comfortable 35
view of all of the cards in the rack without
change of position.

I preferably provide each of the holders or
pockets with a front rail 15 for retaining the
cards in the holders, such rails being preferably 40
transparent glass strips removably retained in
grooves 16 in the end members 2 to prevent con-
cealment of any of the lower portions of the
cards carried in the pockets, and preferably re-
movably seated in the grooves 16 in the end mem- 45
bers 2 and supported on the forward edges of the
cross bars 6, as illustrated particularly in Figs.
2 and 3.

To insure positioning of the cards at the proper
angles in the respective pockets I preferably pro- 50
vide each pocket with a wedge-shaped block 17,
seated on the bottom bars 6, to direct the lower
portions of the cards toward the front of the
pocket and incline the cards for bearing against
the upper portions of the back members, as par- 55

ticularly illustrated in Fig. 2. The blocks 17 for all of the pockets are of the same dimension; consequently, the progressive inclination of the cards heretofore described is not disturbed by the blocks 17.

While the members of the card holder may be assembled together and the assembled holders mounted between the end members 2 in any suitable way, I prefer to first assemble the holders 10 with fastening members, such as nails 18, projected through the upper portions of the back members into the front edges of the respective bottom bars 6, and like fastening members projected through the lower portions of said back 15 members into the rear portions of said bars; then to attach the assembled holders to the end members with nails or like fastening members 19, as particularly illustrated in Fig. 3. An assembly 20 of the holders with the rack ends is uniform when the parts are formed to standard dimensions, the slots 16 for the rails 15 may be formed in the end members 2 and serve as guides for mounting of the card holders.

From the foregoing description it is apparent 25 that cards or other flat articles carried in vertical rows within the holders present their front faces all in planes substantially perpendicular to the lines of vision of a person of average height so that such person may be afforded a comfortable, clear view of all of the cards in the rack 30 merely by raising and lowering his eyes and without the necessity for moving his head or bending his body.

What I claim and desire to secure by Letters 35 Patent is:

1. In a rack of the character described, supporting means, stepped cross-bars fixed to said supporting means having top faces variably inclined to a horizontal plane at the base of said 40 supporting means and having front and rear edges, the lowermost cross-bar having an angular head, one side of which is coincident with and the other perpendicular to said horizontal plane for cooperating with said supporting

means, and back members having top and bottom ends fixed to the front and rear edges respectively of adjacent cross-bars for cooperating therewith in supporting flat cards in planes substantially perpendicular to lines of vision having 5 a common focal point.

2. In a rack of the character described, supporting means having slots, stepped cross-bars fixed to said supporting means having top faces variably inclined to a horizontal plane at the 10 base of said supporting means and having front and rear edges, the lowermost cross-bar having an angular head, one side of which is coincident with and the other perpendicular to said horizontal plane, back members having top and bottom 15 ends fixed to the front and rear edges respectively of adjacent cross-bars for cooperating therewith in supporting flat cards in planes substantially perpendicular to lines of vision having a common focal point, and transparent rails 20 mounted in the slots of said supporting means and cooperating with said bars and back members to form pockets for said cards.

3. In a rack of the character described, supporting means having slots, stepped cross-bars 25 fixed to said supporting means having top faces variably inclined to a horizontal plane at the base of said supporting means and having front and rear edges, the lowermost cross-bar having an angular head, one side of which is coincident 30 with and the other perpendicular to said horizontal plane, back members having top and bottom ends fixed to the front and rear edges respectively of adjacent cross-bars for cooperating therewith in supporting flat cards in planes 35 substantially perpendicular to lines of vision having a common focal point, transparent rails mounted in the slots of said supporting means and cooperating with said bars and back members to form pockets for said cards, and wedge 40 shaped blocks mounted on said bars for directing the lower portions of said cards toward said rails.

JOYCE C. HALL.
